UNITED STATES PATENT OFFICE.

JOHN A. LARSSON, OF BEVERLY, MASSACHUSETTS.

FOLDABLE UMBRELLA.

1,161,139.

Specification of Letters Patent. Patented Nov. 23, 1915.

Application filed November 7, 1911, Serial No. 658,954. Renewed April 14, 1915. Serial No. 21,455.

To all whom it may concern:

Be it known that I, JOHN A. LARSSON, a subject of Sweden, residing at Beverly, in the county of Essex and State of Massachusetts, have invented certain new and useful Improvements in Foldable Umbrellas, of which the following is a specification.

This invention relates to an improvement in foldable umbrellas and the primary object thereof is to provide in a foldable umbrella novel bracing means which are connected through a runner to the ribs and the cloth of the umbrella and are slidably and foldably arranged to occupy but little compass when the umbrella is folded compactly and not in use.

The purpose of the invention is to construct a simple, inexpensive foldable umbrella in which the parts will positively be held in locked position when unfolded.

With the above and other objects in view my invention consists in the combination, arrangement, and details of construction clearly shown in the drawings and then 25 more particularly pointed out in the appended claims.

Similar reference characters designate similar parts throughout the several views of the drawings, wherein,

30 Figure 1 is a vertical elevation of the novel bracing means forming part of my invention, Fig. 2 is a vertical elevation of said bracing means shown in folded position, Fig. 3 is a vertical elevation of a fragmental part of my invention showing the bracing means partially unfolded, Fig. 4 is a vertical elevation similar to Fig. 3 showing the bracing means about to be completely unfolded, Fig. 5 is a vertical elevation partly broken 40 away of the telescoping rods forming the handle of the foldable umbrella, said rods being shown in upraised position, Fig. 6 is a vertical elevation of the telescoping rods shown in a normally inactive position, Fig. 45 7 is a cross sectional view of one of said telescoping rods showing the groove arrangement for preventing the independent rotation of the incased rod.

A ball 1 serves as the bottommost portion 50 of the handle of the foldable umbrella formed by a plurality of telescoping rods of which the lowermost is designated 2. In the hollow rod 2 the hollow rod 3 is slidably mounted in telescoping relation and in the 55 hollow rod 3 is similarly disposed the hollow rod 6 forming, as shown in Fig. 5 the up-

permost end of the handle. To avoid the rotation of any of the telescoping rods, the rods 2, 3, and 6 will be formed, preferably from end to end with a longitudinal concave 60 indentation 4 engaged by corresponding longitudinal indentations 5 formed upon those of the rods which are incased, it being understood that the rod 2 will be formed solely with the convex indentation 4, and 65 the hollow rod 6 solely with the longitudinal concave indentation 5, and the hollow rod 3 with both the longitudinal convex and concave indentations 4 and 5 respectively in order that said rod 3 may slide freely 70 in the rod 2 and in order that the rod 6 may slide freely in the rod 3, and the rotation of any of said rods prevented. The hollow rod 6, will in practice, be of greater length than the foregoing rods and is adapted to 75 receive at its free end the bottom tapered portion of the rod 7 having a head 8, said rod having frictional engagement in the hollow rod 6 and may be slidably disposed therein as shown in Fig. 6, having its head 80 8 engaging the notch member 9 fixed upon the hollow rod 6.

A sleeve 10 is slidably mounted upon the hollow rod 6 and is formed at its outer end with a notch member 11 of preferably 85 greater diameter to which are pivotally secured at circumferential points a series of relatively narrow and shortened rods 12 each being pivoted to a collar 13 through which is passed a relatively longer rod 15 90 pivotally secured to the notch member 16 mounted at the top of the sleeve 17 slidably mounted upon the hollow rod 6. Integral with the collar 13 is a sleeve 14 surrounding the rod 15 and arranged to also embrace the 95 pivotal member 18 connecting respectively the rod 15 and the rod 19, which, at its free end is pivoted to a collar 20 having slidably engagement with a sleeve 21 embracing a rod 24 pivotally secured to the hereinbefore mentioned notch member 9, and fixed upon the hollow rod 6 is an extension 22 being pivoted at 23 to said rod 24. It will be noticed that the arrangement of each and every rod 24 which serves to give the cloth 100 of the umbrella its curvature will be similar as described. Upon the hollow rod 6 is formed the usual spring extension 25 arranged to be moved inwardly to cause the sleeve 17 and collar 10 to be moved to folded 105 position.

The foldable umbrella is to be used as fol-

lows: The spring projection 33 carried at the lower ends of the hollow ribs 3 and 6 respectively will be caused to enter corresponding openings formed in the hollow rods 2 and 3 respectively by sliding the rod 3 in the rod 2, and the hollow rod 6 in the hollow rod 3 a sufficient distance; the rods will thus be held in extended and unfolded position as clearly shown in Fig. 5 and the rigid rod 7 will also be upraised as shown in Fig. 5. When the rods are thus unfolded the rod connections of the umbrella proper will be compactly folded as shown in Fig. 2, the rods 12 and 15 arranged to separate the collar 10 and sleeve 17 on the hollow rod 6, the sleeve 14 on the hollow rod 15 being held at the lower end of said rod, the collar 20 being held by the connecting rod 19 substantially intermediate the ends of the longitudinal sleeve 21, in which sleeve the rod 24 is mounted which is dependingly carried by the notch member 9 and the extension 22 thereof will be folded upwardly, as shown in Fig. 2. The umbrella may then be 25 opened as follows: The extension rod 22 will be unfolded so as to be in alinement with the rod 24 and the sleeve 21 will be raised upwardly and outwardly so as to cause the rods 15 and 24 to be extended obliquely with respect to the hollow rod 6, as shown in Fig. 4, the sleeve 17 being moved downwardly toward the collar 10 to effect this until its notch member 16 will substantially overlie the notch member 11 of 30 said collar, and the arrangement is such that as the sleeve 17 is moved to contact with the collar 10 the rods 12 and 15 will gradually approach the rod 15 moving to a position parallel to the rod 12 when the umbrella is completely unfolded as shown in Fig. 1. The sleeve 17 in moving toward the collar 10 will abut the spring shoulder 25 on the hollow rod 6 and further movement thereof will be restrained, and when 45 the rod 15 occupies its parallel position the sleeve 14 will be in alinement therewith, thereby enabling the connecting rod 19 to be also brought into alinement with the sleeve 14 so that the longitudinal sleeve 21 50 may slide on the rod 24 sufficiently far to be supported and compressed by the foldable connections consisting of the members 14, 15, and 19 respectively. The raising and lowering of the sleeve 17 and collar 10 55 upon the hollow rod 6 determines the folded or unfolded relation of said foldable members and to fold the umbrella it will be necessary to proceed in the reverse manner to the above described mode of operation.

By pressing the spring shoulder 25 inwardly of the rod 6 the folded members shown in Fig. 2 connected to the sleeve 17 and collar 10 may slide below said spring shoulder and by pressing the spring projection 33 inwardly the hollow rods 2, 3, and 6 may be caused to embrace each other as shown in Fig. 6, said spring projection 33 having rounded extremities to facilitate their retraction.

I claim and desire to secure by Letters Patent:

1. A folding umbrella consisting of a staff, a notch fixed thereto, two runners 75 slideable on said staff, a foldable rib pivoted to said notch, a foldable stretcher pivoted to one of said runners and fixed to said rib, a sleeve on said stretcher, a brace pivoted to said other runner and to said sleeve, said foldable stretcher consisting of a pair of members, a link connecting said members, 80 said sleeve adapted to embrace the connection between said link and members, whereby said foldable stretcher is held rigid.

2. A folding umbrella consisting of a staff, a notch fixed thereto, two runners 85 slideable on said staff, a foldable rib pivoted to said notch, a foldable stretcher pivoted to one of said runners and fixed to said rib, a sleeve on said stretcher, a brace pivoted to said other runner and to said sleeve, said 90 foldable stretcher consisting of a pair of members, a link connecting said members, said sleeve adapted to embrace the connection between said link and members, whereby said foldable stretcher is held rigid, and 95 a collar by means of which said stretcher is fixed to said rib.

3. A folding umbrella consisting of a staff, a notch fixed thereto, two runners 100 slideable on said staff, a foldable rib pivoted to said notch, a foldable stretcher pivoted to one of said runners and fixed to said rib, a sleeve on said stretcher, a brace pivoted to said other runner and to said sleeve, said 105 foldable stretcher consisting of a pair of members, a link connecting said members, said sleeve adapted to embrace the connection between said link and members, whereby said foldable stretcher is held rigid, and 110 a collar by means of which said stretcher is fixed to said rib, said rib being telescopic.

In testimony whereof I affix my signature in presence of two witnesses.

JOHN A. LARSSON. [L. S.]
